UNITED STATES PATENT OFFICE.

SAM H. FANNING, OF DALLAS, TEXAS, ASSIGNOR OF ONE-HALF TO HOMER FRADY, OF DALLAS, TEXAS.

FOLDING BOOKCASE.

1,032,054.

Specification of Letters Patent.

Patented July 9, 1912.

Application filed November 25, 1911. Serial No. 662,499.

To all whom it may concern:

Be it known that I, SAM H. FANNING, citizen of the United States, residing at Dallas, in the county of Dallas and State of 5 Texas, have invented certain new and useful Improvements in Folding Bookcases, of which the following is a specification.

This invention relates to improvements in folding bookcases, and has for one of its objects to provide a simply constructed device 10 which may be readily extended to receive the books, pamphlets and the like, and which may be folded into small space for shipment or storage.

15 With these and other objects in view, the invention consists in certain novel features of construction as hereafter shown and described, and then specifically pointed out in the claims, and in the drawings illustrative 20 of the preferred embodiment of the invention: Figure 1 is a perspective view of the improved device in open or operative position; Fig. 2 is a perspective view of the improved device in folded or closed position; Fig. 3 is a section on the line 3—3 of 25 Fig. 1.

Corresponding and like parts are referred to in the following description and indicated in all the views of the accompanying drawings 30 by the same reference characters.

The improved device embraces a body or casing including a top 10, bottom 11, ends 12 and back 13, the back being spaced inwardly from the rear edges of the ends top 35 and bottom as shown. Hingedly connected at 14 to the rear edges of the end members 12 of the body are similarly formed end members 15 which constitute the end members of a bookcase. The top 16 of the bookcase is hingedly united at 17 to the top 10 of the casing, while the bottom member 18 of the bookcase is hingedly united at 19 to the bottom 11 of the body. A plurality of shelves 20 are hingedly united at 21 in the 40 projecting portions of the ends 12 of the body so that the shelves will fold against the back 13 and within the rearwardly projecting portions of the body. The ends of the book shelves when released, fold against the ends 12 of the body, the top 16 of the book shelf portion of the device when released folds over the top 10 of the body, and the bottom 18 of the book shelf portion of the device, folds beneath the bottom 11 of 45 the casing. By this simple means it will be

noted that the body together with its bookcase attachments, are foldable into a small space for convenience when shipping and storing. The shelves 20 are united at their ends in any suitable manner to the end members 15 of the bookcase portion of the device, as for instance by screws 22, so that by simply detaching the screws the bookcase portions may be folded into close relations to the body. 60

The body portion of the device may be provided with a foldable desk 23 and compartments 24 and 25 as shown. The compartment 24 contains a scroll 26 operating over rollers 27—28 to contain drawing 70 lessons, writing copies, or other matter, and readable through an opening 29, the opening being provided with a sliding cover 30. The compartment 25 is supplied with a plurality of maps 31 or the like, mounted on 75 rollers in position to be drawn out over the desk 23 when open. The space in the rear of the desk is occupied with a portfolio device 32 which may be opened over the desk when the latter is in open position. The 80 body 10 is mounted to swing upon a base frame represented as a whole at 33 by a pin 34, and connected to the bottom of the body 10 is a bearing ring 35 while an annular channel member 36 is embedded in the 85 upper member of the base 33 to support a plurality of bearing balls 37. By this means the combined bookcase and desk device is mounted for rotation upon the base. The 90 base is provided with an intermediate transverse shelf 39 and supported upon caster wheels 38.

The improved device may be constructed of any required size or capacity and with any required number of shelves and with 95 shelves of any width or size.

Having thus described the invention, what is claimed as new is:

1. In a device of the class described, a body including a top bottom ends and back, 100 extensions to the ends hingedly united thereto and corresponding in outline to the ends and folded against the outer faces of the same, an extension to the top hingedly united thereto and foldable over the top, an 105 extension to the bottom hingedly united thereto and foldable beneath the bottom, and a plurality of shelves hingedly connected to the body and foldable against the back. 110

2. In a device of the class described, a body including a top bottom and ends and with a back spaced inwardly from the rear edges of the ends top and back, extensions 5 to the ends hingedly united thereto and corresponding in outline to the ends and foldable against the outer faces of the same, an extension from the top and hingedly united thereto and foldable over the top, an extension 10 to the bottom hingedly united thereto and foldable beneath the bottom, and a

plurality of shelves hingedly united relative to the back and foldable within the space between the back and the rear edges of the ends top and bottom.

15

In testimony whereof I affix my signature in presence of two witnesses.

SAM H. FANNING. [L.S.]
